UNITED STATES PATENT OFFICE.

KENNETH L. CROU, OF MOUNDSVILLE, WEST VIRGINIA.

HARNESS-TERRET.

1,303,258.

Specification of Letters Patent. Patented May 13, 1919.

Application filed March 14, 1918. Serial No. 222,452.

To all whom it may concern:

Be it known that I, KENNETH L. CROU, a citizen of the United States, residing at Moundsville, in the county of Marshall and State of West Virginia, have invented certain new and useful Improvements in Harness-Terrets, of which the following is a specification.

This invention relates to harness terrets, 10 and more particularly to a terret provided with rein retaining means.

One of the main objects of the invention is to provide a terret of simple construction and operation provided with means for retaining the hand line or rein in the terret. A further object is to provide a terret having means for preventing turning or twisting of the line, this securing means also serving to normally prevent complete withdrawal of the rein from the terret. Further objects will appear from the detailed description.

In the drawings:

Figure 1 is a front view of a saddle with 25 terrets constructed in accordance with my invention applied thereto,

Fig. 2 is a front view of the terret partly in section to show the means for securing the securing plate in position.

30 The saddle 1 may be of any suitable or standard construction, and is provided with the check rein hook 2 and the terrets 3, positioned equi-distant therefrom. Each terret 3 is in the form of a nearly closed ring,

35 and is provided with a screw stem 4 by means of which it is secured to the saddle. The terret is further provided with a guide and stop plate 5 secured therein and extending at right angles to the axis of the screw stem 4.

40 The body of the terret is provided with notches or recesses which receive snugly the end portions of this plate, and securing screws 6 are inserted through the terret ring and screwed into the ends of the plate. These screws serve to effectually prevent accidental displacement of the plate 5.

The plate is spaced a suitable distance above the lowermost point of the terret ring so as to provide a rein receiving opening 7 intermediate the plate and ring. This opening is of such width as to snugly receive the line or rein so as to permit proper movement thereof while effectually preventing

all play of the rein in the ring and eliminating all possibility of the rein becoming 55 twisted. By this means, twisting or tangling of the rein is avoided. In addition, this terret is of material assistance when the harness is removed, to loop the reins and secure them through the terrets of the saddle. With terrets of ordinary construction, the reins thus become easily twisted and tangled so that it frequently happens that considerable difficulty is caused in straightening the reins out properly, preliminary to 65 securing them to the rings in the bridle. By having the rein pass beneath plate 5, this twisting and tangling is eliminated, and the rein may be easily secured to the bridle ring after which it may be drawn beneath plate 70 5, the plate serving to straighten out any twist which may exist in the rein. By removing the screws 6, the plate 5 may be readily removed from the terret ring so as to permit the reins carried thereby to be 75 completely removed when desired. This ring may be readily applied to any saddle of suitable construction, and may be readily formed from a terret ring of standard construction by the simple expedient of providing the cut-outs or recesses for receiving the end portions of the plate and then securing this plate in position in the manner set forth. For this reason, this terret may be produced at very small cost and may be 80 85 readily applied to a harness saddle of standard construction.

What I claim is:

1. A terret comprising a ring having slots formed transversely thereof, on the interior 90 adjacent the bottom, and a plate spaced from the bottom of the ring and having its ends received in the slots.

2. A terret comprising a ring having slots formed transversely thereof, on the interior 95 adjacent the bottom, a plate spaced from the bottom of the ring and having its ends received in the slots, and screws passing through the ring and engaging the ends of the plate.

In testimony whereof I affix my signature in presence of two witnesses.

KENNETH L. CROU.

Witnesses:

CLARENCE FITZSIMMONS,
J. W. CROU.
